J. KUBLI

TRAFFIC SIGNAL APPARATUS

Filed April 26, 1924

INVENTOR
John Kubli
BY
Conrad W. Kretsch
his ATTORNEY

UNITED STATES PATENT OFFICE.

JOHN KUBLI, OF HUDSON HEIGHTS, NEW JERSEY.

TRAFFIC-SIGNAL APPARATUS.

Application filed April 26, 1924. Serial No. 709,148.

My invention relates to improvements in signaling or sound producing means, and the same has for its object more particularly to provide a simple, efficient and compact apparatus which may be readily and conveniently actuated whereby to control or regulate the traffic on streets, railway crossings or other thoroughfares.

Further, said invention has for its object to provide an apparatus of the character specified in which the signal or sound producing means is actuated by a suitable operating fluid; the flow of which from its source of supply to said signal or sound producing means is manually controlled by the traffic officer or operator.

Further, said invention has for its object to provide an apparatus of the character specified in which the container or receptacle for the operating fluid serves as a base on which the signal sound producing means and the control therefor are mounted.

Further, said invention has for its object to provide an apparatus of the character specified in which one form of valve actuating means may be readily substituted for another in order easily to adapt the apparatus for use under varying conditions of use.

Further, said invention has for its object to provide an apparatus of the character described in which the signal or sound producing device, and the means for controlling the operation thereof are composed of two essential parts which are so constructed and arranged that said parts may be readily detached from each other, and a different form of controlling means substituted in place of the one removed.

Other objects will in part be obvious and in part be pointed out hereinafter.

To the attainment of the aforesaid objects and ends, my invention consists in the novel features of construction, and in the combination, connection and arrangement of parts hereinafter more fully described and then pointed out in the claims.

In the accompanying drawings showing an illustrative embodiment of the invention, Figure 1 is an elevation showing one form

of apparatus constructed according to and embodying my said invention;

Fig. 2 is a vertical sectional view on the line 2—2 of Fig. 1;

Fig. 3 is a transverse sectional view on the line 3—3 of Fig. 2, and

Fig. 4 is an elevation showing a modified form of apparatus with parts broken away and in section.

In said drawings 10 designates a receptacle or tank provided with an inlet 11 through which air or any other suitable operating fluid may be introduced, and maintained under pressure therein. The tank 10 has a substantially flat base 12 on which the apparatus may rest when in position upon a support, which may be the surface of the street or other desirable base.

A tubular member 13 is secured in the top of the tank 10 to communicate therewith, and projects upwardly therefrom. The member 13 is provided with a valve seat 14 therein with which a movable valve member 15 cooperates. A valve stem 16 extends partly above and below said valve member 15 through the perforate guiding members or spiders 17, 17^a which serve to center and guide the stem 16 in its movement therein. The member 17^a is disposed within the upper portion 18 of the tubular member 13 which is threaded. The upper end of the stem 16 is provided with a head 19 located above the upper end of member 13. A spring 20 is interposed between the guiding member 17^a and the head 19 to maintain the valve member 15 normally seated or closed.

The tubular member 13 is adapted to receive either the tubular extension 21 (Figs. 1 and 2), or the tubular extension 21^a (Fig. 4); said extensions being secured within the threaded end portion 18 of the member 13.

The extension 21 has a downwardly extending bracket 22 at one side thereof. A valve actuating member or lever 23 is pivoted at one end 24 to the bracket 22, and extends transversely through the slots 25 in the extension 21 over the head 19 of the stem 16, and is provided at its opposite end with a finger piece 26 for depressing the same. If de-

sired, the lever may be actuated by a chain 27 attached thereto. The lever 23 also extends through slots in a sleeve 28 which is slidably mounted around the extension 21, and covers 5 the slots 25 in order to reduce the leakage of air which might otherwise escape there-through. The arrangement of the lever 23 and the sleeve 28 is such as will permit of pivotal movement of said lever. Secured to the 10 upper end of the extension 21 is the signal device or sound producing member, which is here shown as a whistle 29 adapted to be actuated by the fluid in its passage when the free end of the lever 23 is depressed.

15 In Fig. 4 the valve actuating means consists of a lever 23^a pivoted at one end to the upper end of an upwardly extending bracket 22^a which projects above the upper end of the tubular extension 21^a. The arm 23^a extends 20 transversely across the top of extension 21^a and is provided at its free end with an actuating chain 27^a. The rod 30 is pivoted at its upper end 31 to the central portion of the arm 23^a, and extends downwardly through the 25 upper end of the extension 21^a, and is provided at its inner end with a head 32 which engages the head 19 on the stem 16. The rod 30 is guided and centered by means of a sleeve 33, and by means of the end of said extension 30 21^a through which it slides. When the chain 27^a is drawn downwardly the lever 23^a depresses the rod 30 and opens the valve 15.

It will be noted that each valve actuating means illustrated is arranged to become operatively associated with the head 19 when either extension 21, 21^a carrying the same is secured in position on the tubular member 13. Each extension 21, 21^a may be removed without requiring additional manipulation to disconnect the actuating means carried thereby from the valve stem 16. This feature permits of the use of the apparatus under the varying conditions and as the requirements of operators may render more convenient or desirable.

45 The apparatus being a complete unit is also portable to permit of the same being easily and conveniently moved from place to place.

The actuating fluid, which is preferably air, may be compressed within the receptacle or tank 10 either by a hand pump or a motor driven pump. When it is desired to actuate the signal device or whistle 29, the officer or operator depresses the lever 23 (Figs. 1 and 2) which opens the valve 15 and permits the 50 passage of air from tank 10 through the members 13 and 21, and into the whistle 29 to actuate the same. When the lever 23 is released, the spring 20 returns the valve to closed position. In like manner, when the rod 30 55 (Fig. 4) is depressed by the drawing down

of the chain 27^a the valve 15 will be opened and the air caused to enter the whistle and actuate the same. The valve 15 is closed by spring 20 when the chain 27^a is released.

Having thus described my said invention, 65 what I claim and desire to secure by Letters Patent is:—

1. Apparatus of the character described comprising a receptacle adapted to hold an operating fluid under pressure therein, a tubular member having an end in communication with said receptacle, said tubular member having a valve seat therein, a valve stem guide disposed adjacent the other end of said tubular member, a valve and a valve stem disposed 70 within said tubular member, said stem projecting beyond said other end, a second tubular member disposed in alignment with said first mentioned tubular member and detachably secured to said other end and into which 75 said valve stem projects, a valve operating device carried by said second tubular member, a whistle also carried by said second tubular member, said valve operating device including a member located partly within and 80 partly outside of said second tubular member, that part of said device which is within said second tubular member being arranged to engage the projecting end of said valve stem, and a spring on said stem all being arranged 85 whereby said first tubular member, said valve, said valve seat and said spring constitute one unit, and said second tubular member, said whistle and said valve operating device constitute a second unit, said tubular members 90 having separable connection one with the other for the purposes described.

2. An apparatus of the character described comprising a receptacle to contain an operating fluid under pressure, a first pipe one end 100 of which is secured to and in communication with said receptacle, the other end of which has one element of a detachable joint, a valve seat within said pipe, a valve associated with said seat, a valve stem and a valve stem guide, 105 combined with a second pipe one end of which has the other end of the detachable joint, a valve operating element mounted on said second pipe and in part located within the same, a whistle on said second pipe, said 110 valve stem projecting into said second pipe when said joint elements are assembled and engaging with said valve operating element, all being arranged substantially as and for the purposes described.

Signed at the city of New York, in the county and State of New York, this 29th day of March, one thousand nine hundred and twenty-four.

JOHN KUBLI.
